UNITED STATES PATENT OFFICE.

EDWARD C. SENDELBACH, OF PHILADELPHIA, PENNSYLVANIA.

WOOD DISK WHEEL.

Application filed February 15, 1922. Serial No. 536,672.

To all whom it may concern:

Be it known that I, EDWARD C. SENDELBACH, a citizen of the United States, residing at Philadelphia, in the county of Philadelphia and State of Pennsylvania, have invented certain new and useful Improvements in Wood Disk Wheels, of which the following is a specification.

This invention relates to wood disk wheels 10 and particularly to such wheels for use on automobiles and the general objects of the invention are the provision of a wood disk wheel which is amply strong, readily accommodable to wheel bands of different 15 sizes and easily manufactured.

More specifically stated certain objects of the invention may be said to reside in the provision of what I have termed a double disk wheel, that is a wheel which is made up 20 of two disks or sections as will further appear; the provision of a wheel which presents a flat face to the brake drum as well as a flat face to the hub plate but one which is concaved or dished on the side 25 which is turned away from the vehicle; the provision of a wheel in which the strength of laminated wood is secured but in which none of the glued joints of such laminations are exposed to the weather nor in which are 30 any dirt or water collecting pockets; the provision of a wheel in which the load is carried perpendicularly through the center of the hub and of the wheel band or substantially so; and the provision of a wheel 35 in which the dished front or outer face of the wheel is used to brace the structure against side stress. I also contemplate the provision of a wood disk wheel to which can be readily applied the usual standard wheel 40 band as well as any desired type of hub flange. A further object of the invention is the provision of a wood disk wheel in which ready access can be had to the valve stem for purposes of tire inflation or deflation.

I also propose to build this double disk wheel in such a manner as to utilize the screws or other members which hold the two disks together as a sort of stop against 50 which the rim clamp plates and washers associated with the bolts for holding the rim in place can take.

It is also my intention to provide a wood disk wheel having a flat face against which

the brake drum is secured and an outer 55 dished face which can be entirely made of laminated wood while at the same time being capable of accommodating itself as before stated to different sizes of wheel bands.

These together with such other objects 60 as may appear hereinafter or are incident to my invention I obtain by means of a construction which is illustrated in preferred form in the accompanying drawings, where-
in:

Fig. 1 is a face view of an automobile wheel embodying my invention but with a portion of the rim and some of the rim clamps omitted; Fig. 2 is a section on the line 2—2 of Fig. 1; Fig. 3 is a section on 70 the line 3—3 of Fig. 1 but on an enlarged scale; Fig. 4 is a section on the line 4—4 of Fig. 1 also on an enlarged scale; Fig. 5 is a fragmentary elevation similar to that of Fig. 1 illustrating a modification; Fig. 75 6 is a section on the line 6—6 of Fig. 5; and Fig. 7 is a section similar to that of Fig. 2 but illustrating a somewhat different form of construction.

Referring to the drawings, it will be noted 80 that my improved wood disk wheel comprises a substantially flat back member or section 7 and a dished front member or section 8 which are secured together in any desired or suitable manner but preferably 85 by screws 9 as illustrated. The screws 9 are located near the periphery of the wheel and in addition to these I employ screws 10 nearer the center of the wheel under the hub flange 11.

Because of its very much greater strength I make the back member or section of laminated wood which in the drawings I have illustrated as being composed of seven layers. The number of layers, however, can 95 be varied as desired and I wish to call attention to the fact that by this means I can make my wheel readily accommodable to wheel bands of different sizes. In practice there are generally three standard sizes 100 of wheel bands, namely, $1\frac{1}{2}$ ", $1\frac{3}{4}$ " and 2". In order to make my wheel sufficiently wide at the periphery to take the larger sized bands, I simply add to the number of layers of laminations to the back member leaving the balance of the wheel or rather the parts composing the balance substantially the same in all sizes. This is a very great

advantage and has not been possible heretofore in laminated wood disk wheels where the front or face of the wheel has been dished. In former practice with which I have been familiar, in order to dish the wheel the laminations are built up to a certain thickness and then the entire mass or body of wood is pressed to the desired shape. This process necessarily limited the thickness to which the wheel could be built. It will readily be seen, therefore, that with my improved method it will be possible to build up a wheel to any desired thickness simply by adding laminations to the back member 15 as described.

In Figs. 1 to 6 inclusive I have illustrated the front member or section also as composed of laminated wood which laminations are pressed approximately to the shape illustrated and formed with a central flat portion 12 which abuts against the inner flat face of the back member and a peripheral flat portion 13 against which the rim clamp plates 14 are adapted to be screwed.

Between the flat periphery 13 of the front member and the flat periphery of the back member, I provide a separator 15 and it will be observed that the securing or connecting screws 9 pass through this member.

In order to brace the wheel against side stresses, I apply to the outer face of the flat portion 12 what I have termed a pad extension member 16 which I prefer to make of such a thickness as will make the wheel in the center substantially as thick as it is at the periphery. That is to say the sum of the thicknesses of the back member 7, the front member 8 and the pad extension member 16 is substantially equal to the sum of the thicknesses of the back member 7, the separator member 15 and the flat portion 13 of the front member 8.

Between the pad extension member 16 and the central portion 12 of the outer member 8, I prefer to employ some torque resisting connection such for example as the radially disposed strips of wood 17 which constitute in effect what might be termed keys inasmuch as they fit into suitable channels or grooves in the members which they join. In Figures 5 and 6 I have illustrated a substitute method for resisting torque in which the two members in question are secured together by a plurality of circumferentially disposed dowel pins 18.

In a structure such as is illustrated in Figures 1 to 6 inclusive I prefer to insert a block 19 between the front and back members at the point where the valve stem of the tire, indicated in Figure 2 by the dotted line 20, is inserted. This block is drilled out so as to have an oval opening 21 of sufficient dimension to permit of the use of a pencil pressure gage.

The manner in which the wheel is built

up is briefly as follows: First the desired number of laminations constituting the back member are built up after which the separator member 15 is put in place followed by the block 19 and then by the front member 8. Against the central portion of the front member comes the pad extension member, all the parts being suitably glued step by step. The securing screws 9 and 10 are then put in place and a hole drilled through all of the members at the point where the valve stem is inserted which hole constitutes in effect a continuation of the hole 21 already referred to in the block 19. The rear of the hole is covered over in any desired manner by means of a plate 22 and the front by means of another plate 23 provided with suitable spring clips 24 in order that it may be readily removed and replaced when changing a tire. The spring clips may snap over either the edge of the wood as shown at the upper portion of Figure 2 or over a wire 25 embedded in the wood as shown at the lower portion of the hole in Figure 2.

Referring to Figure 7 it will be noted that the parts substantially correspond with the exception that the front member 8 is not made of laminated wood but is simply built up of a straight piece or a series of straight pieces as may be necessary in forming the wheel. It is also provided with an outer peripheral flat part 13 against which the plates 14 are adapted to abut. This type of wheel is built up in much the same manner as the first type described except, of course, as just stated the outer member 8 is not laminated and instead of pressing it into the dish shape, I prefer to core it out on a lathe.

The wheel band 26 is shrunk on in the usual manner.

It will be noted that the construction provides a smooth flat face against which the hub flange plate 11 is adapted to abut as well as a smooth interior flat face against which the brake drum 27 is adapted to abut. This is of great advantage particularly with respect to the brake drum inasmuch as in former disk wheels of this character with which I am familiar it has been necessary to insert blocking between the brake drum and the inner face of the wheel. Suitable bolts 28 are used to secure the hub flange plate and the brake drum to the wheel.

In Figure 3 I have illustrated in addition to my improvements the usual type of rim 29, rim wedge 30, rim clamp 31 and nut and bolt securing means 32 and 33. I also wish to point out that the screws 9 and the rim plates 14 as well as the washers 34 under the heads of the bolts 33 are so positioned with respect to one another as to bring the rim plates over the heads of the screws and the washers over the ends 130

of the screws. This aids in preventing the parts from being driven or worked into the wood under pressure of the securing nuts 32.

Briefly reviewing, therefore, it will be seen 5 that I have provided a wood disk wheel for an automobile in which I have secured all the advantages incident to laminations while at the same time providing a dished front or outer face. The wheel has a flat back or inner surface against which the brake drum abuts, there are no dirt crevices and the load is carried perpendicularly through the center of the hub and the wheel band. No glued joints are exposed to the weather and the 15 wheel is resilient, light, strong and easy to wash. It is easy to manufacture and presents a pleasing appearance both of which features are of great importance in connection with manufacture and sale.

20 What I claim is:

1. A wood disk wheel comprising in combination, an inner section having substantially flat faces and an outer section inwardly dished to provide a substantially flat 25 central portion abutting against the adjacent flat face of the inner section.

2. A wood disk wheel comprising in combination, a laminated inner section having a substantially flat inner face and an outer section 30 inwardly dished and having a flat inner face adapted to abut against the flat face of the inner section.

3. A wood disk wheel comprising in combination, a laminated inner section having a 35 substantially flat outer face, a laminated outer section having a concave outer face, spacer means between the peripheries of the sections, and securing means holding all of said parts together.

40 4. A wood disk wheel comprising in combination, a laminated inner section having a substantially flat inner face, a laminated outer section inwardly dished to provide a flat faced central portion adapted to abut 45 against the flat face of the inner section, separator means between the peripheries of the sections, and a substantially flat peripheral portion on the outer section adapted to abut against the separator means.

50 5. A wood disk wheel comprising in combination, a laminated inner section having a substantially flat inner face, a laminated outer section inwardly dished to provide a flat faced central portion adapted to abut 55 against the flat face of the inner section, separator means between the peripheries of the sections, a substantially flat peripheral portion on the outer section adapted to abut

against the separator means, and fastening members extending through said peripheral 60 portions and said separator means.

6. In a wood disk wheel for pneumatic tires of the character herein described, the combination of a hollowed block opposite the valve stem into which the stem projects, 65 openings in the disks opposite the block, and removable cap members closing said openings.

7. A wood disk wheel comprising in combination, an inner straight section, an outer 70 inwardly dished section abutting at the central portion thereof against the inner section, and a pad extension member placed against the lowest portion of the dished surface to brace the outer section.

75 8. A wood disk wheel comprising in combination, an inner straight section, an outer inwardly dished section abutting at the central portion thereof against the inner section, a pad extension member placed against the lowest 80 portion of the dished surface, and a key between the pad extension member and the outer section.

9. A wood disk wheel comprising in combination, a laminated inner straight section, 85 an outer inwardly dished laminated section abutting at the central portion thereof against the inner straight section, a pad extension member placed against the lowest portion of the dished surface, and a key between the pad extension member and the outer section.

90 10. A wood disk wheel comprising in combination, a laminated inner straight section, an outer inwardly dished laminated section 95 abutting at the central portion thereof against the inner straight section, a pad extension member placed against the lowest portion of the dished surface, and means locking the pad extension member and the outer section together as against strains imposed by torque.

11. In a disk wheel, the combination with a hub, of a substantially flat laminated disk secured thereto, a curved laminated disk secured to the flat disk at the hub, and a ring separating said disks at their peripheries.

105 12. A disk wheel comprising a substantially flat laminated disk constituting the inner face, and a curved laminated disk secured to the flat disk at the inner portion and spaced apart therefrom at the periphery and constituting the outer face of the wheel.

In testimony whereof, I have hereunto signed my name.

EDWARD C. SENDELBACH.
